BRACE PLATE

Filed April 14, 1926

Mark Taylor Inventor

By Cadmon & Co.
Attorneys.

UNITED STATES PATENT OFFICE.

MARK TAYLOR, OF GAINESVILLE, GEORGIA, ASSIGNOR OF ELEVEN-TWENTIETHS TO
ARTHUR W. BEAUPRIE, OF ATLANTA, GEORGIA.

BRACE PLATE.

Application filed April 14, 1926. Serial No. 102,054.

This invention relates to brackets commonly known as transposition brackets, and has for its primary object to provide means whereby transposition brackets will be securely held to the cross arm of a telegraph pole, to insure against movement of the bracket with respect to the cross arm.

Another object of the invention is to provide a simple attachment that may be attached to either a one point, three point or four point transposition bracket.

A still further object of the invention is to provide brace plates for the brackets that are so constructed that movement of the brackets with respect to the brace plates will be prevented.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view illustrating transposition brackets secured to a cross arm in accordance with the invention.

Figure 2 is a perspective view of one of the brace plates.

Figure 3 is a sectional view taken on line 3-3 of Figure 2.

Referring to the drawing in detail, the reference character 5 indicates a cross arm of a telegraph pole to which the transposition brackets forming a part of the present invention, are secured.

The brackets, which are indicated at 6 and 7 respectively, are of the usual and well known construction, the bracket 6 being constructed to extend downwardly from the cross arm 5, while the bracket 7 extends upwardly therefrom.

The brace plates used in connection with the brackets and which form the essence of the present invention, include body portions

8 each of which being formed of a length of sheet metal and having inwardly extended flanges 9 formed along the side edges thereof, the intermediate portions of the flanges being extended rearwardly as at 10 where they are provided with teeth 11 designed to bite into the cross arm to which the brace plates are secured.

Formed at the upper end of each brace plate is a transversely disposed flange 12 which is relatively long and adapted to rest on the upper edge of the cross arm to which the device is secured, so that the weight of the brackets and wires connected therewith will be transferred from the teeth and flanges 10, to the flanges 12, which are constructed to withstand such strain.

Elongated openings indicated at 13 are formed in spaced relation with each other and provided in each brace plate, which openings are adapted to accommodate the connecting bolts 14 and 15 respectively, the bolt 15 being disposed under the cross arm while the bolt 14 extends therethrough, as clearly shown by Figure 1.

From the foregoing it will be obvious that due to the construction shown and described, the brackets which are positioned between the flanges 9 of the brace plate, will be held against pivotal movement with respect to the cross arm to which they are secured, and the brace plate will also be held against movement with respect to the cross arm by the teeth 11, which become embedded in the cross arm.

It might be further stated that nuts indicated at 16 are provided on the ends of the bolts for securely fastening the brace plates to the cross arm, the bolts and nuts at the same time acting to securely hold the brackets on the brace plate.

I claim:

A plate for use with transposition brackets including a body portion having an elongated inwardly extended flange formed along the upper edge thereof and adapted to rest on the upper edge of a cross arm, the ends of the flange extending appreciable

distances beyond the side edges of the body portion, flanges extending downwardly from the elongated flange and disposed on opposite sides of the body and adapted to rest against the outer face of a cross arm, said body having bolt openings to receive securing bolts, and means on the body portion

for securing a transposition bracket against lateral movement with respect to the body portion.

10

In testimony that I claim the foregoing as my own, I have hereto affixed my signature.

MARK TAYLOR.
